ELECTRICAL SWITCH MECHANISM

Filed Sept. 22, 1927

INVENTOR.
Andrew H. Neureuther

UNITED STATES PATENT OFFICE

ANDREW H. NEUREUTHER, OF PERU, ILLINOIS, ASSIGNOR TO WESTERN CLOCK COMPANY, OF PERU, ILLINOIS, A CORPORATION OF ILLINOIS

ELECTRICAL SWITCH MECHANISM

Application filed September 22, 1927. Serial No. 221,226.

My invention relates to improvements in electrical driving mechanisms for clocks and the like and has for its object the production of a device in which the contacts are closed and opened extremely rapidly or with the so-called "snap" action. A further object is the production of a wiping action when said contacting points are touching each other. A further object is the creation of an actual increased pressure on said contacting point immediately after the initial closing of the circuit takes place, so that the wiping action takes place under the increased pressure placed on the contacting parts thus tending to scrape the contact parts rather than just wiping them.

A further object is to enable the use as much as possible of the lower priced metals for the contacting parts and thereby which together with the simple construction I use, will be very inexpensive to produce and yet be very rigid for service where there is a large amount of vibration and rough usage such as an automobile.

I attain these objects by the means shown in the accompanying drawing in which:

Fig. 1 is a view of one of my driving mechanisms looking at it from the rear and having sufficient of the rear plate removed to show the operative mechanism with the armature of the electro-magnet in its highest position and ready to be actuated by the magnet.

Fig. 2 is a similar view of my driving mechanism showing the armature of the electro-magnet at its lowest position after it has been actuated by the electro-magnet.

Fig. 3 is an enlarged view of the tripping contact mechanism shown in Fig. 1.

Fig. 4 is an enlarged view of a modification of the tripping contact mechanism in the position shown in Fig. 2.

Fig. 5 is an enlarged end view of the contact tripping mechanism shown in Fig. 3.

Fig. 6 is a top view of my driving mechanism shown associated with a clock.

The same numbers represent the same parts throughout the several views.

In the drawing 1 represents the front plate of time movement part of an electric clock,

2 the rear plate of same. 3 represents the front plate of my driving mechanism and 4 the rear movement plate of same. 5 represents the pillars or posts by means of which the plates 1 and 2 are held together and 6 the pillar or posts that holds the plates 3 and 4 together. The driving mechanism is fastened to the clock movement in any of the usual well known means such as indicated by the pillars 7.

Fastened between the plates 3 and 4 is an electro-magnet 8 having cores 9. Pivotedly mounted on a pin 11 adjacent to the electro-magnet 8 is an armature 10 which has an arm 12 projecting therefrom which has pin 13 fastened to it on which is pivotally mounted the pawl 14 whose end 15 engages the teeth 16 of the ratchet wheel 17 which is fastened on a shaft 18 which is journaled in the plates 3 and 4 as shown.

The pawl 14 has a hook 19 to which is fastened one end of a spring 20 the other end of said spring being fastened to a threaded bolt 21 which passes through an aperture in a part 22 projecting from plate 3 which bolt has the nuts 23 by means of which the tension on the spring 20 is adjusted and regulated. A pawl 24 pivoted on a pin 25 and held in engagement with the teeth 16 of ratchet wheel 17 by means of a spring 26 prevents the ratchet wheel 17 from turning in a clock wise direction. It is evident that the spring 20 will pull the pawl 14 against the teeth 16 of gear 17 and rotate it in a counter clockwise direction, and this will occur each time the armature 10 is drawn against the core 9 of the electro-magnet 8.

The forward end of the armature 10 has a contacting plate 34 mounted on the lower part of same but electrically insulated therefrom by means of the insulation 35 shown and said contacting part 34 is electrically connected with one end of the wiring winding on electro-magnet 8 by means of the flexible wire 42 the other end of the wire winding on electro-magnet 8 being connected by means of the wire 37 to a connecting post 38 which is also insulately mounted on the 10

frame or plates as shown and is connected to one line from the source of electrical current. The other line from the source of electrical current is connected to a binding or connecting post 43 mounted directly (grounded) on the frame so that any part not electrically insulated from the frame coming in contact with the contacting part 34 will cause the electrical current to flow through the electro-magnet 8 and energize same.

Mounted between plates 3 and 4 adjacent to the forward end of the armature 10 is a frame 27 which has projecting parts 28 each having an aperture into which are fastened the shoulder pins 29. Pivotaly mounted on said pins 29 is the framed member shown which is built up of the side U-shaped frames 30 and the shafts 31 and 32, the shaft 31 having a roll 33 journaled on the same and the shaft 32 having a contacting roll 36 journaled on same. A pin 39 passes through the members 30 and has one end of a spring 40 connected to same, the other end of said spring 40 is connected through an aperture in a projection 41 from frame 27. The pins 39 and 29 and the projection 41 are so located that they all lie in a straight line when said U-shaped frame 30 is located in its central position and the tension or pull on the spring is such that as soon as the straight line joining the points 39 and the projection 41 passes to the right or left of the point 29, that the spring 40 will trip the frame 30 to the corresponding side. For instance, when the armature is in the position shown in Figure 2 with the roller 33 touching the top of the end of armature 10, the spring 40 is over toward the right side beyond said point 29 and as the right hand end of armature 10 rises due to the pull of the power spring 20 the frame 30 starts to rotate around pin 29 in a clock-wise direction and will do so under the influence of the armature 10 until the straight line from point 39 to 41 above mentioned passes to the left of point 29 when the frame 30 will immediately be "snapped" in a clock-wise rotation until the roller 36 strikes the contacting part 34 on the armature 10 as shown in Figure 1 thus closing the electrical circuit through the wire winding in the electromagnet 8 and energizing said magnet which instantly and extremely rapidly draws the armature 10 down toward the pole pieces 9. It is evident as the armature 10 comes down as above stated that a great pressure is exerted at the point where the surface contacting roll 36 comes into engagement with the contacting part 34 and the surface roller 36 thus rolls over the contacting part 34 thus insuring and maintaining an excellent electrical connection between the contacting roller and the contacting part which will continue until the pivoted frame 30 is returned or "snapped" back into position shown in

Figure 2, breaking the electrical contact and de-energizing the electro-magnet 8 putting the armature 10 again under the control of the stored power spring 20.

It is also evident that the roll 36 will continually, because of it being pivotally mounted, always present a different surface at each closing of the contacts. In the modification shown in Figure 4 where the roller 36 is replaced by a surface 36A it is evident that the surfaces will actually be scraped clean due to the instantaneous great pressure created at the contact points. It is also further evident that the roller 33 and corresponding part 33A can be made of electrically insulating material and the frame 27 electrically insulated from the plates in which case the contacting part 34 would not need be insulated from the armature 10 but could be a part of the "grounded" circuit, the wire 42 in such case being attached to the insulated frame 27.

From the above description it will be seen that my electric driving mechanism is simple and inexpensive to produce and yet is extremely rugged and durable in construction to withstand the severest service and the nature of the making and breaking of the electrical circuits is such that the contacts can be made of the ordinary inexpensive metals instead of from the noble metals and yet avoid sticking and burning of the contact parts thus giving a long and satisfactory service and continuous operation before replacement is necessary.

It will be understood, of course, that while I have here shown and described one form of my invention, I do not wish to limit myself to the exact form shown, but desire to have it taken in a sense illustrative of any or all the forms that come fairly within the scope of my claims.

I claim:

1. In combination, a pivotally mounted actuating element, a contacting part mounted on said element and insulated therefrom, a frame adjacent to said element, a co-operating contacting member comprising two projecting parts adjacent thereto and positioned one on each side of said element, said member being mounted in said frame by means of a pivot in a position substantially away from the center of said member and resilient means so mounted and attached to said frame and said contacting member such that said resilient means will continue the motion of and position said member when same has been moved beyond its centrally disposed position by means of said actuating element.

2. In combination, a pivotally mounted actuating element, a contacting part mounted on said element and insulated therefrom, a frame adjacent to said element, a co-operating contacting member comprising two projecting parts adjacent thereto and positioned

one on each side of said element, contacting means pivotally mounted on each of said projecting parts, said member being mounted in said frame by means of a pivot in a position substantially away from the center of said member and resilient means so mounted and attached to said frame and said contacting member such that said resilient means will continue the motion of and position said member when same has been moved beyond its centrally disposed position by means of said actuating element.

ANDREW H. NEUREUTHER.
